APPARATUS FOR WORKING METALS

Jan Kafow, Long Island City, N. Y.

Application May 16, 1942, Serial No. 443,224

5 Claims. (Cl. 207—9)

This invention relates to an apparatus for working metals and more particularly virgin metal, scrap metal and other metal stock which is melted and cast into a larger ingot and thereafter pressed or extruded in the heat into smaller ingots having a predetermined size and weight for subsequent drop forging or hot pressing into a desired final shape.

In particular, this application forms a continuation in part of my co-pending patent application Ser. No. 374,922, filed January 17, 1941, now Patent No. 2,314,403, issued March 23, 1943. As I have discovered and disclosed in said co-pending application, it is possible to subdivide a larger ingot into a number, two as a minimum, of smaller ingots of a shape and size predetermined by the shape of cavities of a mold or die into which that larger ingot is pressed at proper heat. Any metallic ingot can be so subdivided, whether ferrous or non-ferrous, and particularly consisting, e. g., of aluminum, copper, nickel, zinc, lead, magnesium and their alloys, especially brass and bronze. The optimum temperatures of pressing such larger ingots into smaller ones in a single step appear to be about 40% to 20% below the melting temperature of the metal or alloy, and if brass or bronze are concerned well above about 650° C.

A power driven press in which the larger ingot is so subdivided may be of the friction, hydraulic or steam type, and the pressure may be applied substantially instantaneously or during a short period of time while the ingot is hot and not yet solidified. In the former case a kind of drop forging is applied, confined however to a single stroke of sufficient energy of the forging ram. If a hydraulic or steam driven press is used, the application of pressure should be confined to the smallest possible period of time so that the larger ingot is pressed into the smaller ones while it is hot enough to allow a complete and satisfactory deformation, i. e., without fissures and folds and without causing undesirable strains in the smaller ingots.

In my above mentioned co-pending application, I suggested the use of a mold or die comprising an open receptacle or recess for receiving the larger ingot and thereafter the ram or mold cover for pressing the ingot into the mold cavities communicating with that receptacle. The mold or die consisted of any suitable material, preferably high quality steel, which was hardened after the cavities had been made and particularly machined therein. The individual cavities are of a shape and size corresponding to those

of the smaller ingots to be produced, and in particular of cylindrical configuration. Usually the cavities are equal in size and shape, and longer than the individual smaller ingots. The cross sections of the cavities may be of any desired configuration, such as circular, square, rectangular, etc., and are usually the same over the entire length of the cavities. Taking a given cross section of those cavities and thereby area in a plane vertical to the direction of pressing, the individual size of the smaller ingots depends upon the length of the cavities in the direction of pressing.

I discovered that the same die can be used for the production of a great variety of sizes of smaller ingots. Taking a metallic larger ingot of given size and exerting upon it considerable pressure while it is at proper heat its material will be distributed substantially equally in the cavities and fill them closely whether there is a bottom provided for the cavities or not. Thus with a given cross section and length of the cavities, a number of smaller ingots can be produced therein the horizontal cross section of which corresponds to that of the cavities and the length of which is solely determined by the amount of material pressed into each of them. If the cavities are almost filled by the material pressed into them, the larger ingot or blank from which they are obtained has its maximum size. If the larger ingot is of smaller size, the individual cavities will be filled by the pressed-in ingots to a smaller extent, i. e., the individual smaller ingots will be all of the same cross section again but shorter.

If it is desired to produce smaller ingots of different cross sections, particular dies are to be prepared each time having cavities of such a desired cross section. This results in a stock of a great many dies each comprised of high quality steel and provided with machined-in cavities and hardened thereafter.

It is an object of the invention to reduce the number of dies to be prepared and held in stock for producing smaller ingots of desired horizontal cross section, i. e., in a plane substantially vertical to the direction of pressing.

It is another object of the invention to reduce the amount of valuable high quality steel or similar die material for producing smaller individual ingots of different horizontal cross sections as defined above.

It is still a further object of the invention to reduce the work and cost of preparing dies for producing smaller individual ingots of different horizontal cross sections as defined above.

These and other objects of the invention will be more clearly understood when the specification proceeds with reference to the drawings in which Fig. 1 shows a cross section with some parts in elevation through a die according to the invention, Fig. 2 a perspective view and cross section through a larger ingot particularly usable for the invention, Fig. 3 an elevation of the smaller ingots as obtained after molding a larger ingot and connected by a sort of flash, Fig. 4 a cross section with parts in elevation of a modification of a die according to the invention, and Fig. 5 a cross sectional view taken along line 5-5 in Fig. 4.

In the illustrations of the invention shown in the drawings by way of exemplification, only the essential parts of a molding or extrusion apparatus are shown. As stated above and in my co-pending patent application, the die can be used in any kind of molding, forging or extrusion press.

Referring to Fig. 1, a die holder or receptacle 10 is provided with a recess 30 in which a die proper 11 is fitted. The die is provided with a recess 12 open on top for receiving a larger ingot, and a number, two as a minimum, of holes or cavities 14 which taper downwardly at an incline of, e. g., 1:10. Recess 12 opens into another larger recess on top of the die which has a ring-shaped bottom 36 upon which, if desired, any number of thin, ring-shaped shims 37 can be positioned.

Sleeves or hollow inserts 15 are tightly fitted into the holes 14. Each sleeve is tapered on the outside at the same incline as the holes 14, thereby securing a tight all-over fit. The inside cross section of sleeves 15 is of any desired configuration as stated above, and circular in this exemplification of the invention. Thus, each sleeve 15 is cylindrical inside.

Die 11 may be made of any desired strong material, such as iron or steel, and only sleeves 15 are to be made of high quality material, such as high quality steel, machined to exact shape both outside and inside, and thereafter hardened. The holes 14 may be large enough, e. g., up to an average diameter of 1½", to receive sleeves of different inside diameter, e. g., up to 1". It will be appreciated that the same holes 14 can be used for receiving sleeves 15 of the same outer shape but different inside configurations and sizes corresponding to those of the smaller ingots to be molded therein; thus, only the thickness of the walls of the sleeves or inserts 15 will vary. While, however, according to my previous suggestion a whole die 11 was to be prepared of high quality material, the cavities to be shaped therein to exact size and the die thereafter to be hardened, now, according to my present invention, die 11 can be used for a great many sizes and shapes of smaller ingots to be produced and only sets of sleeves 15 are to be prepared for each required size and shape of the smaller ingots. Thus, a great amount of valuable high quality material for the die is saved. If a given set of sleeves or inserts 15 is worn out during operation, they are to be replaced by new ones which can be used with the same die 11 whereby another substantial saving on material and work in hardening is obtained. It is also easier to machine the relative small inserts; worn out inserts can be bored out to slightly larger diameter and used for producing corresponding ingots 41.

Die holder 10 is provided with a smaller recess

32 below the large one 30 and a hollow member 34 is inserted therein. Member 34 is provided with a number of bores 19 in alignment with holes 14 but of a diameter equaling or smaller than the smallest diameter of the holes in the sleeves 15.

In the hollow space 35 of member 34, a plunger or plate 22 is slidably arranged and connected with rod 26.

Holes (not shown) may be provided in plate 22 permitting communication between space 35 and the outside air.

Ejecting rods 20 are slidably arranged in each hole 19 and seated upon or connected with plate

15 22.

In assembling the die, member 34 is first inserted into recess 32 and seated on its shoulder 33 formed by the bottom portion 23 of the die holder 10. Thereafter die 10 with sleeves 15 tightly and accurately fitted therein, is fitted into recess 30 and seated upon shoulder 31 of that recess. Subsequently, rods 20 are slipped through the holes 19 and plunger 22 inserted into the hollow cylindrical space 35.

In operation, a blank 38, Fig. 2, of cylindrical shape and properly heated is inserted into recess 12 and almost fills it, and thereupon a plunger or ram 39 having a reduced projection 40 is pressed upon the blank in the manner described in my above identified co-pending application.

Preferably an instantaneous blow is thus exerted upon the blank or larger ingot. There may also be used a hydraulic or steam press, and the pressure acting upon plunger or ram 39 be rapidly increased so as to press the hot ingot as fast as possible and before it cools and solidifies, into the cavities formed by the holes of inserts 15.

Fig. 1 shows ram 39 in its lowermost position 40 after having exerted an instantaneous blow or sufficiently high pressure upon the blank or larger ingot so as to press the latter in a single step into the holes of inserts 15 and to form therein the desired smaller ingots 41 which are connected 45 by a sort of flash 42.

The horizontal cross sections of the smaller ingots 41 correspond to those of the holes in the inserts 15, and they are of equal length within very small tolerances. The thickness of flash 50 42 is determined by the size of the larger ingot and the extent to which ram portion 40 is pressed into recess 12. The sizes of the larger ingots can be kept equal within small tolerances in their production; hence, the end position of ram portion 40 determines the size of the smaller ingots 41 as well as of flash 42. In order to adjust those sizes as exactly as possible either ram 39, 40 can be machined so accurately that ram 39 strikes shoulder 36 just when individual ingots 60 41 and a flash 42 of predetermined sizes are produced. If flashes 42 of different thicknesses are desired, different rams would become necessary. In order to avoid it at least to a certain extent, thin shims 37 are placed upon shoulder 36 in such a number that the same ram will come to rest at different distances from shoulder 36 wherefrom different desired thicknesses of flash result.

After the larger ingot has just been transformed into smaller ingots 41 connected by a flash 42, as shown in Fig. 3, plunger or plate 22 is moved upwardly by rod 26, while ram 39, 40 is lifted simultaneously, and the ejector rods 19 eventually eject the ingots 41. By breaking up flash 42, the individual ingots 41 are separately

recovered, and can now be subjected to subsequent shaping processes, e. g., forging or pressing, and given either immediately the desired ultimate shape of a finished article ready for use or an intermediary shape suitable for further shaping processes.

It will be appreciated that the hot initial larger ingot cools down during its deformation in the die, and the smaller ingots cool further, shrink somewhat away from the interior surfaces of sleeves 15 and solidify whereby the subsequent ejection of those smaller ingots is facilitated. During pressing or molding, the larger ingot is densified. During cooling a desired crystalline or grain structure is applied to those ingots. The relatively large mass of the mold or die secures a rate of cooling which prevents any quenching action; if the latter be desired, the die 11 or die holder 10 should be provided with channels through which a cooling medium is circulated.

As I disclosed in my above mentioned co-pending application, I discovered in casting metallic bodies that holes, deep depressions or fissures can be successfully avoided if certain dimensions are imparted to the body. I found optimum results if the height *a* (or largest vertical dimension), Fig. 2, is about half the diameter *b* (or largest horizontal dimension) of the ingot or blank 38. It is understood that by using a larger or initial ingot of those approximate proportions, a highly dense initial ingot is pressed into smaller ingots which retain that density or, if possible, are even more densified by the pressure exerted for deformation.

Referring to Figs. 4 and 5, the die holder 10 is provided with a single substantial cylindrical recess in which a cylindrical member 18 is fitted, on top of which a plate member 17 is placed provided with large holes 19 and secured in proper position by set screw 43. Above member 17, the die proper 11 is fitted. As distinguished from the exemplification of the invention according to Fig. 1, holes 14 in die 11 are tapered upwardly, and so are sleeves or inserts 15 on their outside. The latter are tightly fitted into the holes 14 and held in this position by plate member 17.

Ejector rods 20 are provided with enlarged heads 21, which are slidably arranged in the cylindrical holes or cavities 16 of sleeves 15 and thereby apt to form a bottom within and of those cavities.

It will be appreciated that upon placing a larger hot ingot into recess 12 upon its shoulder 13, and exerting pressure upon that ingot, it will be squeezed into and fill the holes 16 and, if the size of the larger ingot be large enough, the smaller ingots will be seated upon and their lower ends shaped by the heads 21 then acting as bottoms of cavities 16. It will further be appreciated that by adjusting the position of plate or plunger 22 within space 35, also the position of the heads or bottoms 21 in the cylindrical cavities 16 can be adjusted and thereby the size of the smaller ingots determined. In such case, ram 39 should not be stopped by shoulder 36 or shims 37 in order to secure that the cavities are filled completely by the material of the larger ingot even if there are very small but unavoidable differences in the sizes of those larger ingots. If, however, the horizontal dimension of recess 12 is large enough to give space for flashes of different horizontal extents, such stops of the downward stroke of ram 39 can well be applied; the result will be that slightly larger initial blanks result in a flash of larger horizontal dimension.

It should be understood, however, that a die as shown in Fig. 4 can be used the same way as a die shown in Fig. 1, i. e., that the individual smaller ingots do not become seated on top of heads 21 but end in some distance therefrom, as is assumed and shown in Fig. 1.

It is sometimes difficult to align the reciprocating ram 39, 40 exactly with die 11 so that ram portion 40 in its lowermost position is exactly centered within recess 12 or with respect to the usually symmetrically arranged cavities in inserts 15. In order to facilitate such alignment or centering, die holder 10, Figs. 4 and 5, is provided with a somewhat eccentric flange 44 having a conical outer surface 45. A ring 28 is provided with an inner conical surface of the same incline as surface 45, and can be fastened by a number of screws 29 to a support 46. In order to bring die 11 and its recess 12, Fig. 4, in exact alignment with ram 39, 40, the axis and path of which is determined once and for all by the structure of the press, screws 29 are somewhat loosened and die holder 10 turned within ring 28 until the former's axis is in exact alignment with that of the ram; thereafter screws 29 are tightened. It is also possible to turn ring 28 relative to die 10 and to fasten it in any one of the six positions determined by the screws 29. It will be understood that by enlarging the number of screws and/or by providing a larger number of threaded holes in support 46 to receive those screws, the number of positions of ring 28 relative to die 10 and its flange 44 can be increased to any desired extent. Of course, both methods described above for centering die 10 relative to the ram can be combined, i. e., die 10 turned within ring 28, and the latter turned relative to support 46.

Holes 25 serve to permit escape of air during assemblage and similar holes (not shown) can be provided below plate 22 and communicate with other holes or channels (not shown) in support 46. If it is desired to establish an open communication between the space below plate 22 and the outside.

While I have described above specific advantages of my present improvement, it should be understood that all the other advantages ascribed to my basic invention in my above identified co-pending application apply the same way to the invention presently described. It should be further understood that my invention is not limited to the specific features herein set forth, but to be derived in its broadest aspects from the appended claims.

55. What I claim is:

1. For combination with a power press, such as an extrusion press, a die having opposite fronts, a first and larger cavity in said die opening in one of said fronts for receiving an ingot or blank and a pressing ram, a plurality of second cavities in said die of considerably smaller cross sections than that of said first cavity, said second cavities opening at one end into said first cavity and at the other end into the second of said fronts, said second cavities tapering toward one of their ends, and individual hollow inserts exchangeably fitted into said second cavities and opening flush with the latter into said first cavity, each such insert tapered at its outside the same way as the cavity into which it is fitted and shaped at its hollow inside conforming to the individual configuration to be applied to metallic material to be pressed therein.

2. For combination with a power press, such as an extrusion press, a die of iron or steel having

opposite fronts, a first and larger cavity in said die opening in one of said fronts for receiving an ingot or blank and a pressing ram, a plurality of second cavities in said die of considerably smaller cross sections than that of said first cavity, said second cavities opening at one end into said first cavity and at the other end into the second of said fronts, said second cavities tapering toward one of their ends, and individual hollow inserts of hardened high quality steel exchangeably fitted into said second cavities and opening flush with them into said first cavity, each said insert tapered at its outside the same way as the cavity into which it is fitted and shaped at its hollow inside conforming to the individual configuration to be applied to metallic material to be pressed therein.

3. In combination with a power press, such as an extrusion press, for subdividing a larger ingot into a plurality of smaller ones, a die having opposite fronts, a first and larger cavity in said die opening in one of said fronts for receiving an ingot or blank and a pressing ram, a plurality of second cavities in said die of considerably smaller cross sections than that of said first cavity, said second cavities opening at one end into said first cavity and at the other end into the second of said fronts, said second cavities tapering toward one of their ends, hollow inserts exchangeably fitted into said second cavities, each such insert tapered at its outside the same way as the cavity into which it is fitted and shaped at its hollow inside conforming to the shape to be applied to metallic material to be pressed in said die, a die holder provided with a recess into which said die is fitted, mounting means exemplified by a ring for mounting said die holder on a support, and projecting means exemplified by a flange associated with said die holder, said mounting and projecting means adjustably engaging one another along a conical surface arranged slightly eccentrically to the centre axis of and tapering toward said die.

4. In combination with a power press, such as an extrusion press, for subdividing a large ingot into a plurality of smaller ones, a die having opposite fronts, a first and larger cavity in said die

opening in a third still larger cavity of slight depth, said third cavity opening in one of said fronts, said first cavity arranged for receiving an ingot or blank and a pressing ram provided with a laterally projecting shoulder to enter into said third cavity, a plurality of second cavities in said die of considerably smaller cross sections than that of said first cavity, said second cavities opening at one end into said first cavity and at the other end into the second of said fronts, said second cavities tapering toward one of their ends, hollow inserts exchangeably fitted into said second cavities, each such insert tapered at its outside the same way as the cavity into which it is fitted and shaped at its hollow inside conforming to the shape to be applied to metallic material to be pressed in said die, and removable means as exemplified by shims arranged within said third cavity for determining the lowermost position of said shoulder and thereby said ram for pressing an ingot placed in said first cavity into the hollow spaces of said inserts.

5. For combination with a power press, such as an extrusion press, a die having opposite fronts, a first and larger cavity in said die opening into one of said fronts for receiving a metallic ingot or blank and a pressing ram, a plurality of second cavities in said die of considerably smaller cross-sectional areas than that of said first cavity, said second cavities opening at one end into said first cavity and at the other end into the second of said fronts, said second cavities tapering towards one of their ends, individual hollow inserts exchangeably fitted into said second cavities and opening flush with the latter, each said insert tapered at its outside in the same way as the cavity into which it is fitted and shaped at its hollow inside conforming to the individual configuration to be applied to metallic material to be pressed therein, and a die holder in which said die is seated, said die holder including a member against which said die and inserts therein abut at the second of said fronts.

JAN KAFOWI.
